UNITED STATES PATENT OFFICE

159,775

PROPELLING ATTACHMENT FOR BOAT RUDDERS

Edgar Belmont, Port Chester, N. Y.

Application May 19, 1949, Serial No. 2,754

Term of patent 14 years

(Cl. D71—1)

To all whom it may concern:

Be it known that I, Edgar Belmont, a citizen of the United States and a resident of Port Chester, county of Westchester, and State of New York, have invented a new, original, and ornamental Design for a Propelling Attachment for Boat Rudders, of which the following is a specification, reference being had to the accompanying drawings, forming part thereof.

Fig. 1 is an elevational view of a propelling attachment for boat rudders from one side thereof, showing my new design;

Fig. 2 is an elevational view, on an enlarged scale, from the opposite side thereof, part of the fin being broken away;

Fig. 3 is plan view of Fig. 2;

Fig. 4 is a perspective view of the propelling

attachment viewed from the same side as Fig. 1, part of the fin being broken away; and

Fig. 5 is a perspective view of the propelling attachment viewed from the same side as Fig. 4, but at a different angle, part of the fin being broken away.

I claim:

The ornamental design for a propelling attachment for boat rudders, substantially as shown.

EDGAR BELMONT.
